[57] **CLAIM**

The ornamental design for a removable thermal liner for coveralls, as shown and described.

DESCRIPTION

FIG. 1 is a front elevational view of a removable thermal liner for coveralls showing my new design;

FIG. 2 is a rear elevational view thereof;

FIG. 3 is a side elevational view as seen from the left of FIG. 1, the side not shown being a mirror image of the side shown;

FIG. 4 is a top plan view thereof; and

FIG. 5 is a bottom plan view thereof.

FIG. 3

FIG. 4

FIG. 5
